UNITED STATES PATENT OFFICE.

JAMES C. DAWSON, OF WEBSTER GROVES, MISSOURI, ASSIGNOR TO ELMA N. DAWSON,
OF WEBSTER GROVES, MISSOURI.

LOOSE-LEAF BINDER.

Application filed September 8, 1925. Serial No. 54,940.

This invention relates to loose leaf binders and has for its principal object to permit the paper holding prongs to be firmly held in closed position and yet be easily opened. Further objects and advantages of the invention will become apparent as the description is read in connection with the accompanying drawings in which

Fig. 1 is a plan view of a loose leaf binder embodying the invention, a portion of the cover being broken away to reveal the operating mechanism;

Fig. 2 is a side elevation partly in longitudinal section on the line 2—2 of Fig. 1;

Fig. 3 is a transverse section on the line 3—3 of Fig. 1;

Fig. 4 is an end view;

Fig. 5 is a transverse section on the line 5—5 of Fig. 2;

Fig. 6 is a plan view of a fragment of the blank from which the resilient base plate is formed, and

Fig. 7 is a perspective view of one of the operating levers.

A pair of toggle plates 10—10 are articulated at their adjacent edges by double headed buttons 11 and have their remote edges pivotally mounted in the flanges 12 of a resilient base plate 13. The toggle plates carry pairs of paper holding prongs 14 and 15 which are opened when the toggle formed by the two plates is bent upwardly, and closed when it is bent downwardly. In order to enclose the operating parts and give the binder a finished appearance a resilient cover 16 is sprung over the flanges 12 and has flanges 17 which grip the base plate and hold the cover firmly in place. Such a cover adds somewhat to the pressure on the remote edges of the toggle plates, but its chief function is to enclose the mechanism from above and contribute to the finished appearance.

Each end of the binder is provided with an operating lever including an outer arm forming a thumb piece 18, an inner arm 19 projecting beneath the toggle plates adjacent to their inner margins and an intermediate portion 20 connecting the two arms and fulcrumed on the margins of the base plate. According to the preferred construction the intermediate portion 20 of the operating lever projects slightly above the end of the cover plate as shown in Fig. 2 so as to place the thumb piece 18 in a con-

venient position and also prevent the thumb from coming in contact with the end of the cover plate. The sides 21 of the intermediate portion are curved substantially in accord with the curvature of the base plate 60 at its side portions and form trunnions on which the operating lever is fulcrumed.

The contact between the trunnions 21 and the base plate is well out towards the edges only of the latter. Hence, when pressure 65 is applied to the thumb piece the lever presses downwardly on the side margins of the base plate and upwardly on the inner margins of the toggle plates. As a result the lever has a decided tendency to flatten 70 out the base plate and thus relieve the pressure against the remote edges of the toggle plates and make it easy to straighten the toggle.

The base plate is formed from a blank 75 having the configuration indicated in Fig. 6 and in addition to being bent roughly to a semi-ellipse its edges are turned inwardly along the lines 22 and thereby grooves, or pockets, 23, are formed in which 80 the remote edges of the toggle plates bear and are easily retained. The ears 24 of the blank are bent downwardly, as indicated in Fig. 4, and the ears 25 are bent upwardly 85 to secure the operating levers in place on the end portions of the base plate that projects a short distance beyond the ends of the cover 16.

The thumb piece 18 is curved substantially parallel to the cover 16 and projects at 90 each side, as indicated at 26, over the edges of the base plate and protects the fingers from the corners of it.

Heretofore operating levers have been fulcrumed on the base plate either directly 95 in the middle thereof or along the intermediate portion. When pressure was applied it tended to increase the concavity of the base plate, and, therefore, the pressure against the remote edges of the toggle 100 plates, thereby increasing the resistance to upward bending of the toggle in opening the prongs.

With levers constructed and arranged according to this invention the pressure of 105 the toggles is directed as indicated by the arrows 27 in Fig. 4, and operates to relieve the pressure on the toggle and permit it to be easily straightened by the inner arm 19 of the lever. Hence, with such levers the 110

pressure on the toggle can be made sufficient to firmly hold the prongs closed and give them a snappier movement and at the same time the prongs can be easily opened by pressing downwardly on the thumb piece 18.

I claim as my invention:

1. In a loose leaf binder, the combination of pairs of paper-holding prongs, a pair of toggle members articulated at their adjacent edges to form a toggle adapted to bend upwardly to separate the pairs of prongs and to bend downwardly to bring the prongs together, a base plate beneath the toggle members and having flanges in which the remote edges of the toggle members are pivoted, an operating lever comprising an outer arm forming a thumb-piece, an inner arm projecting beneath the toggle, and an intermediate substantially upright portion connecting the two arms and having its side portions fulcrumed on the margins of the base plate adjacent to the flanges.

2. In a loose leaf binder, the combination of pairs of paper-holding prongs, a pair of toggle members articulated at their adjacent edges to form a toggle adapted to bend upwardly to separate the pairs of prongs and to bend downwardly to bring the prongs together, a resilient base plate beneath the toggle members and having flanges exerting a yielding pressure on their remote edges, and an operating lever comprising an outer arm forming a thumb-piece, an inner arm projecting beneath the toggle, and an intermediate substantially upright portion connecting the two arms and having its side portions fulcrumed on the margins of the base plate adjacent to the flanges.

3. In a loose leaf binder, the combination of pairs of paper-holding prongs, a pair of toggle members articulated at their adjacent edges to form a toggle adapted to bend upwardly to separate the pairs of prongs and to bend downwardly to bring the prongs together, a base plate beneath the toggle members and having flanges in which the remote edges of the toggle members are pivoted, and an operating lever comprising an outer arm forming a thumb-piece, an inner arm projecting beneath the toggle, and an intermediate substantially upright portion forming an end closure for the base plate and having its side portions fulcrumed on the margins of the base plate adjacent to the flanges.

4. In a loose leaf binder, the combination of pairs of paper-holding prongs, a pair of toggle members articulated at their adjacent edges to form a toggle adapted to bend upwardly to separate the pairs of prongs and to bend downwardly to bring the prongs together, a base plate beneath the toggle members and having flanges in which the remote edges of the toggle members are pivoted, an operating lever comprising an outer arm forming a thumb-piece, an inner arm projecting beneath the toggle, an intermediate substantially upright portion forming an end closure for the base plate and having its side portions fulcrumed on the margins of the base plate adjacent to the flanges, and bent ears on the end of the base plate securing the lever in place.

5. In a loose leaf binder, the combination of pairs of paper-holding prongs, a pair of toggle members articulated at their adjacent edges to form a toggle adapted to bend upwardly to separate the pairs of prongs and to bend downwardly to bring the prongs together, a base plate beneath the toggle members having inwardly curved flanges in which the remote edges of the toggle members are pivoted, and an operating lever comprising an outer arm forming a thumb-piece, an inner arm projecting beneath the toggle, and an intermediate portion notched to receive the flanges of the base plate and having its side portions fulcrumed on the base plate adjacent to the flanges.

6. In a loose leaf binder, the combination of pairs of paper-holding prongs, a pair of toggle members articulated at their adjacent edges to form a toggle adapted to bend upwardly to separate the pairs of prongs and to bend downwardly to bring the prongs together, a base plate beneath the toggle members having inwardly curved flanges in which the remote edges of the toggle members are pivoted, an operating lever comprising an intermediate portion forming a closure for the end of the base plate projecting above it and notched to receive the flanges, a fulcrum on the base plate adjacent to the flanges, an outer arm projecting from the top of the intermediate portion to form a thumb-piece, and an inner arm projecting beneath the toggle.

In testimony whereof I affix my signature.

JAMES C. DAWSON.
